WELLHEAD CONSTRUCTIONS

William W. Word, Jr., Houston, Tex., assignor to Armco Steel Corporation, Middletown, Ohio, a corporation of Ohio

Filed Sept. 20, 1963, Ser. No. 310,367
5 Claims. (Cl. 166—6)

This invention relates to well apparatus and particularly to wellhead constructions. Though of broader utility, the invention is especially directed to solving problems involved in the installation of wellhead constructions under water.

Wellhead constructions serve to position and support casing, tubing and the like upright elongated members which extend down the bore hole, to seal off the top of the well, and to conduct various fluids in controlled fashion. Further, wellhead constructions must be characterized by substantial flexibility of purpose, since they are employed at operational stages ranging from drilling to production. Through long years of development, various types of wellhead constructions have, to a considerable extent, become more or less standardized insofar as general structural features are concerned, though there are relatively modern problem areas which, like multiple completion wellhead installations, have stimulated present-day advances of fundamental importance. At the present time, the industry is undertaking the installation of wells under novel conditions presenting problems which differ both in kind and in severity from the problems encountered in every-day well practice. These conditions are encountered in the establishment of producing wells drilled in the floor of a body of water, with the wellhead construction usually installed substantially at the floor of the body of water and therefore remote from the surface by a distance which may range from less than 100 feet to as much as 15,000 feet.

In the case of a wellhead installation on dry land, all of the operational wellhead parts are either visible or accessible with relative ease. Hence, for example, if a hanger element secured to a casing string is to be lowered into the wellhead, so as to seat properly on a supporting member, this operation presents relatively little difficulty because the descent of the hanger element can be observed in relation to the wellhead body and the supporting member. Further, it is a relatively simple matter to back off the casing string and try again when necessary. Similarly, the problems of obtaining proper alignment between body members, and between sealing elements and bores, for example, are greatly simplified at ground level because of the relative ease with which the parts can be observed and manipulated manually. Problems of attaching one member to another, as in the case of securing an upper head member to the top of a lower head member, are also handled with relative ease at ground level.

When the wellhead construction is to be installed at a considerable depth under water, however, even those problems which are simple at ground level become exceedingly difficult. It is obviously impractical, for instance, to consider bolting two head members together at depths below the surface of the sea greater than attainable by a diver. Similarly, the problems of properly seating a member in the body of a wellhead at such a depth has been likened to threading a needle at fifty paces in the dark.

A broad objective of this invention is to device an improved construction for installing and suspending upright elongated members, such as casing and tubing, in a well.

Another object is to provide an improved, more effective and dependable, wellhead construction.

2

A further object is to provide a wellhead construction, especially suited for underwater installation, wherein casing or the like can be suspended successfully even though, because of jamming or otherwise, the casing is not lowered fully to the intended position.

Yet another object is to devise a wellhead or like apparatus for suspending casing, tubing, and the like, which provides, in addition to a fixed-shoulder or equivalent supporting means, an alternatively useful, normal inactive slip assembly which can be brought into effective operation by remotely controllable power means situated at the wellhead.

In order that the manner in which these and other objects are attained in accordance with the invention can be understood in detail, reference is had to the accompanying drawings, which form a part of this specification, and wherein:

FIGS. 1 and 1A constitute a view, partly in vertical section and partly in vertical elevation, of an underwater wellhead construction in accordance with one embodiment of the invention, illustrating casing and tubing strings supported by shouldered hanger mandrels, only a fragmentary portion of the upper body member of the wellhead construction being shown;

FIG. 2 is a transverse sectional view, taken on line 2—2, FIG. 1A;

FIG. 3 is a view, partly in vertical section and partly in vertical elevation, of the lower one of two hanger members employed in the wellhead construction of FIGS. 1 and 1A;

FIG. 4 is a transverse sectional view taken on line 4—4, FIG. 1A;

FIG. 5 is a view, partly in vertical section and partly in elevation, of one of the hanger mandrels employed in the wellhead construction of FIGS. 1 and 1A;

FIG. 6 is a view, similar to FIG. 1A, showing the wellhead construction with one casing string supported by slips and the upper end of that casing string packed off in accordance with the invention; and

FIG. 7 is a view, partly in vertical section and partly in elevation, of the seal or pack-off device employed in the construction seen in FIG. 6.

FIGS. 1—7 illustrate a wellhead construction which is particularly adapted for successful installation at considerable depths under water. In this embodiment, the wellhead construction comprises a lower body member 1 attached in sealed relation to the upper end of an outer casing 2. As will be apparent from FIGS. 1 and 1A, this wellhead construction is adapted to support, under various conditions of installation and use, a surface casing 3, a production casing string 4, and a tubing string 5. At its upper end, lower body 1 supports an upper body member 6. Lower body member 1 has a vertical through bore, indicated generally at 7, which accommodates a lower hanger member 8 and an upper hanger member 9. Both hanger members 8 and 9 cooperate with a set of selectively actuatable, power operated slips, described in detail hereinafter. Additionally, when employed in the manner seen in FIGS. 1 and 1A, lower hanger member 8 supports a lower hanger mandrel 10 while upper hanger member 9 supports an upper hanger mandrel 11. Surface casing 3 being hung from the lower hanger mandrel 10 while production casing string 4 is hung from the upper hanger mandrel 11.

The upper body member 6 is also provided with a vertical through bore indicated generally at 12 which is vertically aligned with through bore 7 of lower body 1. The tubing string 5 is suspended from a support member 13 mounted in the lower end of bore 12.

Suspension of casing 3

Immediately above the upper end of outer casing 2 lower body 1 is provided with a pair of opposed laterally directed ports 14. Above these ports the diameter of through bore 7 is markedly increased to provide an upwardly facing downwardly and inwardly slanting annular shoulder 15. Save for porting and ducting hereinafter described bore 7 extends as a plain cylinder upwardly from shoulder 15.

Lower hanger member 8 is of tubular form and is provided at its lower end with a frusto-conical end face of such shape as to seat in face-to-face contact with shoulder 15. Thus, engagement of the lower end face 16 of hanger member 8 on shoulder 15 provides rigid support for the lower hanger member, as seen in FIG. 1A. Adjacent its lower end, the inner surface of member 8 is cut away to provide a downwardly and inwardly slanting, frusto-conical, slip-supporting surface, indicated at 17. Immediately above surface 17, the wall of tubular member 8 is substantially greater in thickness than it is at the top of the surface 17, so as to provide an intermediate body portion 18 which can be considered as joined to the slip-supporting surface 17 by a transversely extending shoulder 19. The upper end of intermediate body portion 18 is defined by a transverse, annular shoulder 20 slanting downwardly and inwardly and lying parallel to the bottom end face 16. Above shoulder 20, upper portion 40 of member 8 is of reduced thickness, so as to accommodate hanger mandrel 10 in the manner hereinafter described.

Intermediate body portion 18 of member 8 is provided with at least three equally and circumferentially spaced downwardly opening vertical cylinder bores directed generally toward slip-supporting surfaces 17, each of these bores slidably accommodating a cylindrical plunger 21. A laterally extending, outwardly opening port leads to the upper end of each of the cylinder bores and, as will be seen in FIG. 1A, the length of the plungers 21 is such that, when their lower ends are substantially flush with shoulder 19, their upper ends engage the upper ends of the cylinders which accommodate them and are disposed to be acted upon by hydraulic fluid supplied through the ports 22. It will be noted that the upper end of each plunger 21 is tapered, providing a surface against which hydraulic fluid supplied via port 22 can act downwardly to initiate downward movement of the plunger. Each plunger 21 is provided with a groove carrying an O-ring to provide a seal between the plunger and the wall of the bore accommodating the same.

In the region of slip-supporting surface 17, member 8 is provided with three circumferentially and equally spaced vertical slots 23, each such slot opening outwardly into an outwardly opening recess 24. Slidably disposed on surface 17 is a slip assembly consisting of three identical slip segments 25. Each segment 25 is in the form of a downwardly tapering wedge-like member having a frusto-conical outer surface of such size and shape as to lie in flush face-to-face contact with surface 17. Each segment has a toothed, or otherwise suitably interrupted, inwardly directed working face 26 and an upwardly exposed transverse end face 27 which extends below one of the plungers 21. On its outer face, each segment 25 is provided with a vertically extending, radially outwardly projecting guide flange 28 slidably disposed in the corresponding slot 23. The flange 28 cooperates with its slot 23 to accurately guide the slip segment in its vertical movement along supporting surface 17. Thus, the slot 23 can have vertical side walls and flange 28 can be of rectangular transverse cross section so as to present side walls in sliding engagement with the side walls of the slot. A pair of vertically spaced retaining elements 29 are threaded or otherwise suitably secured in guide flange 28 and have enlarged head portions disposed in recess 24, the space between the enlarged heads of elements 29 and the outwardly facing shoulders between slot 23 and recess 24 is filled by an as-

sembly of spring washers, or any other suitable elements, so that elements 29 function to retain slip segment 25 in sliding engagement with the surface 17. In this connection, it will be noted that the inner wall of recess 24, which forms the shoulders at the slot 23, is disposed parallel to surface 17, so that slot 23 is of constant depth.

At least one inwardly projecting shear pin 30 is secured in member 8 for each slip segment 25 and is spaced below shoulder 19 by a distance only slightly greater than the vertical length of the slip segment. Shear pins 30 project inwardly from surface 17 and hold the segments 25 in a raised, inactive position, so that the working faces 26 of the slip segments will be spaced outwardly from the casing member which they may ultimately be called on to support. With the segments in raised position, the upper end face 27 of each slip segment will lie in contact with the lower end of the corresponding one of plungers 21. It will thus be apparent that, if hanger member 8 is seated, with its lower end 16 in contact with shoulder 15 of member 1, the slip segments 25 will normally be held in raised, inactive position by the shear pins 30 but can be driven downwardly, sliding along surface 17, if sufficient hydraulic pressure is applied, via ports 22, to cause plungers 21 to apply a downward force to the slip segments which is adequate to break shear pins 30. Each segment 25 carries a pin 30', FIG. 2, which projects into a bore in the adjacent segment, the bore being of slightly larger diameter than the pin. Thus, if one segment is forced downwardly to break its shear pin 30 before the other segments, the pins 30' will prevent further major downward travel until all of shear pins 30 have been broken and all of the segments can descend together.

Near its lower end, each slip segment 25 is interrupted by a deformable body of packing material which extends 35 completely through the slip segment from the working face thereof to the outer face which engages supporting surface 17. Indicated at 31, this packing is capable of providing a fluid-tight seal between the outer surface of casing 3 and supporting surface 17. Packing 31 can be 40 provided in any suitable fashion, as by making the same in the form of a joint between two separate metal portions making up the body of the slip segment, the packing material being adhesively bonded to the metal.

Lower end 16 of member 8 is provided with at least one upwardly and inwardly inclined bore which accommodates a locator pin 32. Pin 32 is urged outwardly, so as to project from the surface of end 16, by a compression spring disposed within the bore and is retained within the bore by a snap ring seated in a suitable groove 50 in the wall of the bore adjacent the mouth thereof. Shoulder 15 is provided with a circularly extending transverse groove 33 so located that, when the lower end 16 of member 8 is seated on shoulder 15, locator pin 32 will project into groove 33. Groove 33 is of generally 55 V-shaped transverse cross section, with the lower wall of the groove extending substantially horizontally and with the upper wall inclined at the same angle as is the bore for locator pin 32. Spaced from the bottom of the V of groove 33, an upwardly extending ridge or flange 34 projects from the lower wall of groove 33. Flange 34 is provided with a notch capable of snugly embracing locator pin 32. Hence, when member 8 is lowered into seated position on shoulder 15, it can be rotated until locator pin 32 falls into the notch in flange 34. When that occurs, member 8 will be rotationally located with respect to body 1 in such fashion that any given point on the outer surface of member 8 will be radially aligned with a definite point on member 1. With this in mind, it will be noted that a laterally extending through port is provided 60 in the wall of member 1, as indicated at 35, at a position such as to be aligned with one of the ports 22 when locator pin 32 is disposed in the notch in ridge or flange 34. Of course, a plurality of ports 35 are provided, one for each of the ports 22. Further, the inner surface of member 1 is provided with a shallow, inwardly opening,

circularly extending transverse groove 36 which interconnects the inner ends of ports 35. At points which will lie respectively above and below groove 36, when member 8 is seated on shoulder 15, member 8 is transversely grooved and provided with annular packings 37 held in compression between member 8 and body 1 to seal off the area of ports 35 and make certain that hydraulic pressure applied through these ports is conducted to ports 22.

At a point spaced above ports 35, at least one larger laterally directed through port 38 is provided in the wall of member 1. Member 8 is provided with a through port 39 which is coaxially aligned with port 38, when member 8 has been rotationally located in proper position by locator pin 32.

The upper portion 40 of member 8 presents a circularly extending, transverse, downwardly and inwardly slanting surface 40' which, as will be later described, acts as a shoulder to support upper hanger member 9.

Lower hanger mandrel 10 is of tubular form, the lower end thereof presenting a circularly extending, transverse, downwardly and inwardly slanting surface 41 adapted to seat in flush, face-to-face contact with the upwardly directed shoulder 20 presented by member 8. At its bottom end, hanger mandrel 10 is interiorly threaded for rigid connection to the exteriorly threaded upper end of surface casing 3. Adjacent the lower end thereof, hanger mandrel 10 is provided, at its outer surface, with a pair of circularly extending, transverse grooves containing O-ring seals for engagement with a cylindrical inner surface provided by the portion of member 8 above shoulder 20. It will thus be understood that hanger mandrel 10 can be threadedly attached to the upper end of the last length of casing 3 installed and, as this length of casing is lowered through body 1 so that the lower end of the hanger mandrel seats on shoulder 20, the casing string 3 will then be rigidly supported on body 1, via member 8, and a fluid-tight seal will be effected between hanger mandrel 10 and body 8, and hence between casing 3 and member 8, by the O-ring seals 42.

At a point spaced well above its lower end, mandrel 10 is provided with a least one lateral bore slidably accommodating an outwardly biased latch pin 43 in the manner described and claimed in Patent 3,171,674, issued Mar. 2, 1965, to Paul E. Bickel and William W. Word, Jr. In the manner fully described in said patent, pin 43 is urged outwardly by a compression spring accommodated behind the same and is retained in place by a catch of any suitable form. Pin 43 is provided with a short tip of smaller diameter than the bore which accommodates the locator pin, the tip being connected to the main body of the pin by a portion presenting an upwardly facing downwardly and outwardly slanting camming surface 43'. At a distance above shoulder 20 suitable for receiving pin 43 when hanger mandrel 10 is seated on shoulder 20, the inner surface of member 8 is provided with a transverse annular groove 44 into which the projecting tip of pin 43 can extend when the hanger mandrel is in proper seated position. Groove 44 is provided with a radial locator stop (not shown) disposed to be engaged by pin 43. Hence, when mandrel 10 is lowered into place, and so seats on shoulder 20, pin 43 snaps into groove 44 and rotation of the mandrel can bring pin 43 into engagement with the locator stop, thus rotationally locating the hanger mandrel with reference to member 8. From FIG. 1A, it will be noted that this rotational location serves to align a lateral through port 45, provided in mandrel 10, with the through port 39 in member 8 and, hence, with port 38 in body 1. Thus, the interior of casing string 3 is placed in communication with port 38.

The vertical length of hanger mandrel 10 is such that the upper end thereof is disposed slightly below end surface 40' of member 8 when the hanger mandrel is seated on shoulder 20 as seen in FIG. 1A.

Suspension of casing string 4

Upper hanger member 9 is similar to member 8 and includes a circularly extending, transverse, downwardly and inwardly tapering lower end face 46 of such extent and configuration as to come into flush, face-to-face contact with the upwardly directed face 40' provided at the upper end of hanger member 8. Thus, assuming hanger member 8 to be in place, as seen in FIG. 1A, lowering of upper hanger member 9 into body 1 will bring lower end face 46 of member 9 into seated engagement with the upper end face of lower hanger member 8. Member 9 presents a circularly extending, downwardly and inwardly slanting, frusto-conical slip-supporting surface 47 and has a vertically short intermediate body portion 48, portion 48 presenting a downwardly directed, outwardly inclined, transverse face 49 which lies at right angles to the slip-supporting surface 47. Intermediate body portion 48 also presents an upwardly directed, downwardly and inwardly inclined, circularly extending face 50 disposed to support the upper hanger mandrel 11.

Hanger member 9 carries a slip assembly comprising three transversely arcuate slip segments 51 of generally wedge-shaped vertical cross section. Each slip segment 51 presents an inwardly directed, interrupted working face 52, an arcuate outer face of such configuration as to slidably engage supporting surface 47, and a flat upper end face 53 which extends at right angles to supporting surface 47. Member 9 is provided with three vertically extending guide slots 54, each arranged to cooperate with one of the slip segments 51, and each opening outwardly into a recess 55, in similar fashion to the corresponding elements described with reference to member 8. Each slip segment 51 is provided with a vertically extending, upwardly projecting guide flange 56 which is slidably disposed in the corresponding one of guide slots 54. A pair of vertically spaced retaining elements 57 have their inner ends secured in the guide flange 56 and include enlarged head portions disposed in recess 55. Spring washers or other suitable spacing means are disposed between the enlarged heads of retaining elements 57 and the shoulders formed by guide slots 54, the inner face of recess 55 again extending parallel to the slip-supporting surface so that the retaining elements serve to maintain slip segment 51 constantly in slidable engagement with the slip-supporting surface.

A plurality of cylinder bores, including at least one for each slip segment 51, are formed in member 9 in such fashion as to open through face 49 and to be disposed parallel to slip-supporting surface 47, each such bore accommodating a cylindrical plunger 58. A generally lateral duct 59 is provided for each cylinder bore, so that hydraulic pressure can be applied to the upper ends of the plungers 58 in substantially the same fashion hereinbefore described with reference to operation of plungers 21. It will be seen that each plunger 58 is disposed to move along a line at right angles to the flat upper end face of the corresponding one of slip segments 51, this line of movement being parallel to slip-supporting surface 47.

Member 9 carries at least one shear pin for each slip segment 51, as indicated at 60, the shear pins 60 being disposed for engagement by the lower edges of the slip segments. Thus, shear pins 60 serve to hold the slip segments in a raised, inactive position, in which position they engage the lower ends of plungers 58. It will be obvious from FIG. 1A that, when adequate hydraulic pressure is applied to the plungers via ducts 59, the plungers will operate to force slip segments 51 downwardly, breaking shear pins 60, so that the slip segments can come into good supporting engagement with the outer surface of casing 4. As described with reference to suspension of casing string 3, slip segments 51 are each provided with a suitable packing 61 to effect a fluid-tight seal between the outer surface of casing 4 and slip-supporting surface 47.

when the slips are actuated into casing-supporting position.

At its lower end, member 9 is provided with at least one bore, normal to lower end face 46, to accommodate a locator pin 62. Upper end face 40 of member 8 is provided with a generally V-shaped groove 63, corresponding precisely to groove 33, to receive locator pin 62. The lower, horizontally disposed wall of groove 63 is formed with an upwardly projecting ridge or flange 64 having an upwardly opening notch into which the tip of locator pin 62 can fall. Locator pin 62 is again resiliently biased outwardly, in the same fashion hereinbefore described with reference to pin 32. When member 9 has been seated on the shoulder provided by the upper end of member 8, with locator pin 62 disposed in the notch in ridge or flange 64, member 9 is rotationally oriented with respect to the member 1 in such fashion that each point on the outer surface of member 9 is coincident with a definite point on the inner surface of member 1. A plurality of through ports 65 are provided in the wall of member 1 in such locations that, when member 9 is rotationally oriented in the manner just described, each port 65 will register with a different one of the ducts 59. Member 9 is provided with a pair of vertically spaced, transversely disposed, circularly extending packings 66 located to seal off the area of ports 65 when the parts are assembled as shown. The inner face of member 1 is again provided with an annular groove extending in such fashion as to include the inner ends of ports 65, so that all of these ports thus lead to a common, sealed space.

Well above shoulder 50, a through port is provided in member 9. With member 9 located rotationally by locator pin 62 as hereinbefore described, port 67 is radially aligned with a through port 68 in the wall of member 1.

Upper hanger mandrel 11 is identical with lower hanger mandrel 10, earlier described. Thus, mandrel 11 has a downwardly and inwardly tapering bottom end face adapted to seat on shoulder 50 presented by member 9. The lower end of mandrel 11 is internally threaded so as to be rigidly connectable to the externally threaded upper end of the last length of casing making up casing string 4. O-ring seals are provided to effect a fluid-tight seal between mandrel 11 and member 9 immediately above shoulder 50. Mandrel 11 carries a resiliently outwardly biased latch pin 69, and member 9 is provided with a transverse annular groove to receive pin 69, a stop or abutment (not shown) being provided in the groove so that pin 69 can be engaged with the stop or abutment both to rotationally position mandrel 11 and to allow the threaded joint for the handling tool to be broken when the mandrel is installed. Mandrel 11 has a through port 70 aligned with ports 67 and 68, as shown, so that port 68 is in communication with the interior of casing string 4.

Suspension of tubing string 5

At its top, body 1 is provided with an outwardly projecting transverse flange 71 which is chamfered, as indicated at 72, at its upper peripheral corner. Immediately below flange 71, body 1 is provided with an outwardly open, circular extending, transverse groove 73, the top wall 74 of which slants downwardly and inwardly.

Upper body member 6 is provided at its lower end with an outwardly projecting flange 75 of considerably greater diameter than flange 71. The outermost portion of flange 75 presents a downwardly facing, upwardly and inwardly inclined, frusto-conical guide surface 76 which joins an upwardly extending cylindrical surface 77, as shown. Surface 77 is concentric with through bore 12 and has a diameter only slightly larger than the diameter of flange 71. Surface 77 surrounds what may be termed a bottom face 78 which is concentric with bore 12. Adjacent surface 77, face 78 is provided with a groove which opens downwardly and is defined by an outer cylindrical side wall, forming a continuation of surface 77, an inwardly and upwardly slanting wall portion 79, and a horizontally

extending annular surface 80 constituting the bottom of the groove. At top flange 71, the inner surface of body 1 is downwardly and inwardly slanted, providing a sealing surface 81. Bottom face 78 of member 6 is connected to face 80 by a downwardly and inwardly slanting surface 83, forming the inner side wall of the groove in member 6 which accommodates flange 71. As it slants downwardly and inwardly, surface 83 diverges from surface 81, providing a space to accommodate an annular metal sealing ring 84 which is provided for the purpose of sealing between the top of body 1 and the bottom of body 6.

It will be noted that the flange 75 can be considered as including an annular skirt, surrounding flange 71, the skirt having a substantial vertical dimension and projecting well below flange 71 when body 6 is seated on body 1, as shown. Thus, with the parts assembled as seen in FIG. 1, a substantial portion of the skirt surrounds but is spaced from groove 73. At each of three points spaced circumferentially and equally around flange 75, the skirt portion thereof is provided with horizontally extending, inwardly opening bores, one of which is seen at 85. Each bore 85 has an inner portion 86 of smaller diameter and an outer portion 87 of larger diameter, the two portions joining at a transverse annular shoulder 88. Disposed within each bore 85 is a latching plunger 89 having a smaller portion slidably disposed in bore portion 86 and a larger portion slidably disposed in bore portion 87, these two portions of the plunger being joined by a transverse shoulder 90. A helical compression spring 91 surrounds the portion of plunger 89 which is of smaller diameter and is engaged between shoulders 88 and 90 so as to urge the latch plunger outwardly. Ducts 92 and 93 are provided, each communicating with a different end of larger portion 87 of the bore 85. O-ring seals are provided on each plunger to effect a fluid-tight seal between the plunger and the wall of the bore 85 in which it is disposed.

Each latch plunger 89 is of such length that, when hydraulic pressure is applied to the bore via duct 92, the plunger can move to the right (as viewed in FIG. 1) and, before spring 91 becomes fully compressed, tip portion 94 of the plunger will enter groove 73. At its free end, tip portion 94 is chamfered at an angle corresponding to the angle of inclination of the top wall 74 of groove 73. Hence, when plunger 89 is moved into full engagement in groove 73, the chamfered tip surface of the groove comes into face-to-face engagement with wall 74.

It will be understood that, when hydraulic pressure is applied via duct 93, and fluid can exhaust from bore 85 via duct 92, the latch plunger will be moved to the left until it is fully retracted, that is, until the tip thereof is wholly within bore 85. With the latch plungers all in this position, it will be obvious that body 6 can be lowered to seat upon the upper end of body 1, guide surface 76 serving to center body 6 with respect to body 1.

As body 6 is lowered, the skirt portion of bottom flange 75 thereof descends into surrounding relation about flange 71 and groove 73, and surface 80 comes into face-to-face engagement with the annular top face of flange 71. When member 6 has been fully lowered into position, hydraulic pressure can then be applied via duct 92, causing the latch plungers to move inwardly until their inner tips engage in groove 73. In this connection, the chamfer at the tip of each plunger engages downwardly and inwardly slanting wall 74, so that a tight compressive fit is provided between flange 71 and the groove defined by surfaces 79, 80 and 83. As body 6 becomes fully seated on body 1, seal 84 is placed under great compression between surfaces 81 and 83, so effecting a good fluid-tight seal between the two bodies.

The lower end portion of body 6 is provided with a centrally located dependent portion 95. Within portion 95, bore 12 is provided with a downwardly and inwardly slanting shoulder portion 96. Tubing string 5 is supported from shoulder portion 96 by hanger element 13, which

has an upper end portion of a larger diameter, to fit within the main portion of bore 12, a lower end portion of smaller diameter, and an intermediate portion tapering inwardly and downwardly to come into face-to-face contact with shoulder portion 96. The lower end portion of hanger element 13 is internally threaded for attachment to the externally threaded upper end of tubing string 5. Element 13 is provided with an intermediately located groove carrying an O-ring sealing element to establish a fluid-tight seal between element 13 and shoulder portion 96. It will be understood that the bore 12 can freely pass tubing string 5 and that the tubing string can be suspended simply by attaching hanger element 13 to the last section of tubing installed, so that the hanger element comes into seated relation in member 6 as the tubing string is finally lowered.

Upper body 6 can be of any suitable configuration and, in accordance with the usual practice, will support an additional head member or members, as indicated at 97. The head member next above body 6 can be latched in place thereon by means of latching plungers, provided in the same fashion hereinbefore described with reference to latching plungers 89.

Assembled in the manner illustrated in FIGS. 1 and 1A, the well head construction of this embodiment operates to suspend the tubing string and casing strings 3 and 4 from hanger elements which are of the mandrel type and which are seated directly on rigid shoulders afforded by the upper and lower bodies and the upper and lower tubular hanger members. To attain the assembly illustrated in FIGS. 1 and 1A, it is of course necessary that the casing strings 3 and 4 descend to the desired, predetermined depth, without jamming. Thus, under normal circumstances, all of the tubular strings will be supported by mandrel type elements and the two sets of slips will remain inactive, the slip segments 25 and 51 retaining their disengaged position, as illustrated in FIG. 1A.

Assume, on the other hand, that hanger mandrel 10 has been attached to the upper end of the last piece of casing in casing string 3 but that, as the casing string is then further lowered, the string becomes jammed before the hanger mandrel can seat on shoulder 20 of member 8. This condition is easily detected because the latch pin 43 will not have engaged in groove 44 and application of an upward strain to the casing string is effective to raise the string. Under these circumstances, it is necessary to provide support for the casing string, sever the string just below the hanger mandrel in order to recover the latter, and then pack off the casing string. In order to accomplish this in accordance with the embodiment of the invention illustrated in FIGS. 1-7, the slip assembly comprising slip segments 25 is first actuated by supplying hydraulic pressure, via ports 35 and ducts 22, to actuate plungers 21 downwardly, driving the slip segments 25 downwardly along supporting surface 17, shear pins 30 being ruptured in the process, and the slip segments ultimately coming into a position such that the working faces 26 thereof are positively engaged with the adjacent outer surface of the tubing string. Slip segments 25 are thus caused to be wedged between casing 3 and the slip-supporting surface 17, so that the slips support the weight of the casing in conventional fashion.

A casing cutting tool is then run down and, being first located relative to the top of member 8 in such fashion that the cut will be just below ports 38 and 39, is operated to cut through the casing so that hanger mandrel 11 can be recovered. A seal, indicated generally at 98, and shown in detail in FIG. 7, is then lowered into place and set to pack off the upper end of casing 3, providing a fluid-tight seal between the casing and member 8.

Seal 98 comprises a lower annular member 99 having a downwardly and inwardly slanting surface 100, FIG. 7, of such shape and disposition as to be engageable in face-to-face relation with the shoulder 20 presented by member 8. Lower member 99 has a flat annular upper

face 101 and cylindrical outer and inner surfaces 102 and 103, respectively. The radial thickness of annular member 99 is only slightly less than the spacing between the adjacent inner face of member 8 and the outer surface 5 of casing 3. At its upper, inner edge, member 99 is provided with an annular notch defined by plain cylindrical surface 104 and downwardly and inwardly slanting surface 105, surfaces 104 and 105 being connected by a transverse or horizontal surface 106. At its upper end, member 99 is provided with a plurality of circumferentially spaced, upwardly opening, vertical bores 107.

Seal 98 also comprises an upper annular member 108 which is considerably elongated as compared to lower member 99. Upper member 108 has a plain cylindrical 15 inner surface 109 and a flat, annular, transverse bottom face 110 disposed above face 101 of member 99. At its lower inner edge, member 108 is provided with an annular transverse notch defined by upright cylindrical surface 111 and upwardly and inwardly slanting surface 112, 20 surfaces 111 and 112 being joined by an intermediate transverse surface 113. A plurality of vertical, downwardly opening, circumferentially spaced bores 114 are provided in member 108 to cooperate with bores 107 in member 99. The circumferential spacing of bores 114 and 107 is identical, so that pairs of the bores may be vertically aligned as shown in FIG. 7. In alternate pairs of bores 107, 114, there are disposed helical compression 25 springs 115. Headed retaining studs 116 are disposed in the remaining pairs of bores 107, 114, retaining pins 117 being carried by member 108 and projecting each into a different bore 114 to engage below the heads of studs 116 and thereby limit the space between faces 101 and 110 to a distance less than the relaxed length of springs 115.

35 A packing ring 118, deformable under compression, is disposed in the space between surfaces 105 and 106, on the one hand, and 112 and 113, on the other hand. In transverse cross section, packing ring 118 has the general configuration of a T, the arms forming the crossbar of the 40 T projecting into contact with the slanting surfaces 105 and 112, respectively, and the end of the stem of the T being engaged with surfaces 104 and 111, the width or vertical dimension of the packing ring being such that, when the ring is relaxed, the same will bridge the gap between faces 101 and 110 when the heads of studs 116 are engaged with retaining pins 117, as seen in FIG. 7.

The lower portion of member 108 has the same radial thickness as low member 99. The upper portion of member 108, however, is substantially thinner and includes an 45 outer surface portion 119 which is exteriorly threaded at the upper end of member 108 for engagement with the interior threads of a setting tool 120, FIG. 7. At its upper end, member 108 is provided with an outwardly and downwardly slanting surface 121 serving as a guide for the tip of the setting tool 120. Below the exteriorly threaded portion, the wall of member 108 is provided with a lateral port 122 which, as will be explained, is adapted for alignment with port 39 in member 8 when the seal 98 is set.

In its lower portion, member 108 is provided with an 50 outwardly opening cylindrical recess 123 in which is slidably disposed a latch pin 124. An axial bore is provided in the inner end face of latch pin 124 and accommodates a compression spring 125 which, engaged between the latch pin and the bottom end wall of recess 123, urges latch pin 124 outwardly. Latch pin 124 is held in recess 123 by a suitable retaining member 126.

Assuming that casing 3 has been severed in the manner hereinbefore described and that setting tool 120 has been 55 attached to seal device 98, it will be obvious that the setting tool can be manipulated to lower the seal until bottom face 100 thereof engages shoulder 20 on member 8. Further lowering of the setting tool will then cause springs 115 and packing ring 118 to be compressed to such an extent that faces 101 and 110 come into flush engagement. As will be clear from a comparison of FIGS.

6 and 7, the vertical distance between shoulder 20 and latch pin 124, when faces 101 and 110 are engaged, is substantially equal to the vertical distance between shoulder 20 and groove 44. Hence, lowering the seal, by manipulation of setting tool 120, to such an extent as 5 to cause the seal to seat on shoulder 20 and faces 101 and 110 to come into contact, will result in latch pin 124 snapping into groove 44. Such engagement of pin 124 in groove 44 serves both to retain seal 98 in its set position and to rotationally locate the seal in such manner 10 that port 122 is aligned with port 39. Engagement of latch pin 124 in groove 44 holds upper member 108 of the seal device rigidly in place with respect to member 8, because of the radial stop in groove 44 engaged by pin 124, so that settling tool 120 can now be detached from 15 the seal device and withdrawn upwardly.

Referring to FIG. 6, it will be apparent that a closed annular space is defined by the outer surface of casing 3, cooperating with surfaces 104-106 and 111-113. The transverse cross section of this annular space is substantially smaller than the transverse cross-sectional area 20 of the packing ring 118 when the packing ring is relaxed. Hence, when seal device 98 is set as hereinbefore described, so that the parts thereof occupy the positions seen in FIG. 6, packing ring 118 is compressively deformed and provides a fluid-tight seal between members 99 and 108 and the outer surface of the adjacent casing 3. Both members 99 and 108 are provided with outwardly opening transverse annular grooves which receive O-ring packing 30 elements 127 and 128, respectively, which provide a fluid-tight seal between the outer surfaces of seal device 98 and the adjacent inner surface presented by member 8.

From FIG. 6, it will be apparent that ports 122 and 39 place the interior of casing 3 in substantially direct 35 communication with port 38 in body 1.

Referring again to FIG. 1A, it will be seen that body 1 and hanger member 8 combine to form support means from which casing 3 is suspended, the passage through the hanger member including both the slip-supporting surface 17 and the seat 20. While this construction is 40 advantageous for certain well installations, it will be understood that the invention is not limited to constructions in which the hanger is an element separate from the body member.

It is also to be understood that the invention can be 45 practiced with various types of pack-off devices instead of that illustrated in FIG. 7. Thus, for example, pack-off devices such as those described in detail in copending application Ser. No. 302,994, filed Aug. 19, 1963, by Edward E. Castor et al., can be employed.

What is claimed is:

1. Wellhead apparatus adapted for installation under water, comprising in combination support means adapted to be installed under water and defining an upright passage dimensioned to pass a 55 pipe to be suspended from said support means, said passage being defined in part by a downwardly and inwardly tapering slip-supporting surface, said passage including an upwardly facing transverse seat located above said slip-supporting 60 surface;

a plurality of slip segments operatively carried by said support means for movement between a raised inactive position, in which said segments are spaced outwardly from the pipe to be supported when the pipe is disposed within said passage, and a lowered active position on said slip-supporting surface, in which position said segments will operatively engage the pipe to support the same; 70

means carried by said support means for releasably retaining said slip segments in said raised inactive position;

power means carried by said support means and operatively arranged to actuate said slip segments from 75

said raised inactive position to said lowered active position;

a pipe suspending member adapted to be secured to the well pipe and dimensioned for downward insertion into said passage,

said suspending member having a downwardly facing surface dimensioned for engagement with said seat;

means operative for determining, from a point remote from the underwater location of said support means, whether or not said suspending member is disposed with said downwardly facing surface in engagement with said seat; and

a unitary annular packing device dimensioned for downward insertion into said passage into engagement with said seat to seal between said support means and the pipe to be suspended when, the pipe having failed to descend far enough for engagement of said suspending member with said seat, said slip segments are actuated into engagement with the pipe by said power means and said suspending member is then removed.

2. Wellhead apparatus according to claim 1 and where-

in said support means comprises

a body member having upright passage means therethrough, and

a hanger member dimensioned for downward insertion into the passage means of said body member,

said body member and hanger member having co-operating shoulder means operative to support said hanger member on said body member, said hanger member defining said upright passage and including said slip-supporting surface and said seat.

3. Wellhead apparatus according to claim 2 and where-

in said hanger member includes a portion disposed above said slip-supporting surface and projecting inwardly from the top thereof, said portion being provided with a plurality of downwardly extending bores, said power means comprises a plurality of pistons each slidably disposed in a different one of said bores and operatively arranged relative to one of said segments to force the same downwardly as the piston is moved downwardly in its bore, and

said means for operating said power means includes a plurality of ducts in said hanger member each communicating with a different one of said bores above the corresponding one of said pistons and opening outwardly toward said body member, and duct means provided in said body member and communicating with said ducts for supply of pressure fluid thereto when said hanger member is supported on said body member by said shoulder means.

4. Wellhead apparatus according to claim 1, wherein said means operative for determining whether or not said suspending member is disposed with said downwardly facing surface in engagement with said seat comprises

an inwardly opening detent groove in said support means, said groove opening into said passage and being located above said seat,

at least one detent member carried by said suspending member and arranged for movement between a retracted position and a laterally projected position, said detent member being aligned with said groove when said suspending member is disposed with said downwardly facing surface in engagement with said seat, and means carried by said suspending member for actuating said detent member outwardly into engagement in said groove.

5. Wellhead apparatus according to claim 4, wherein said packing device comprises
- a lower annular member engageable with said seat, an upper annular member arranged above said lower annular member, said lower and upper annular members cooperating to define an inwardly opening annular packing-accommodating space,
- an annular packing element disposed in said packing-accommodating space,
- said lower and upper annular members being relatively movable axially of said packing device, at least one detent member carried by said upper annular member and arranged for movement between a retracted position and a laterally projected position, and
- means carried by said upper annular member for actuating said detent member outwardly into engagement in said groove,
- the dimensions of said annular members and said packing element, and the location of said detent member on said upper annular member,

5

being such that, when said lower annular member is engaged with said seat and said upper annular member is so positioned that said detent member engages in said groove, said packing element is compressively deformed by said lower and upper annular members.
